(57) **CLAIM**

The ornamental design for a paper towel holder, which is a power saving paper towel dispenser, as shown and described.

DESCRIPTION

FIG. 1 is a perspective view of a paper towel holder showing our new design.

FIG. 2 is a side elevation view thereof;

FIG. 3 is an opposite side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The features shown in broken lines depict unclaimed portions of the paper towel holder and environmental subject matter only and form no part of the claimed design.

1 Claim, 7 Drawing Sheets
